PHOTOGRAPHIC PRINTING APPARATUS

Fordyce E. Tuttle and Joseph Stoiber, Rochester,
N. Y., assignors to Eastman Kodak Company,
Rochester, N. Y., a corporation of New Jersey

Application November 28, 1940, Serial No. 367,596

6 Claims. (Cl. 95—73)

The present invention relates to photographic printing apparatus, and particularly to a contact printer having more even light distribution over the printing window than customary, and to a new and improved paper masking means for use therewith.

One object of the present invention is to provide a paper masking means for a photographic printing apparatus by means of which different margins and different sizes of exposed areas on a sensitive printing paper can be readily and accurately obtained.

Another object is to provide a masking means of the type set forth which includes two masking strips which are manually individually adjustable relative to a paper stop, the adjusting member of each masking strip including a margin scale adapted to cooperate with an index on the paper support in definite relation to said paper stop, and by means of which margin scale and indices the masks can be readily set to provide any desired margin on two edges of the sensitive paper positioned by said stop.

And another object is to provide a masking means of the type set forth in which each of the adjusting members for the two mask strips above described includes a second scale movable therewith and over each of which a pointer connected with one of two other masking strips is adapted to be moved to adjust said last-mentioned masking strip relative to the first-mentioned masking strip to obtain any desired size of exposed area and a desired margin on the other two edges of the paper.

And a further object is to adapt a masking means of the type set forth to a contact printer so that the adjusting scales of the individual masking strips will be visible in the dark so that the same can be readily adjusted in a darkroom.

And another object of the present invention is to provide a masking means of the type set forth and in which the masks and scales connected thereto are mounted in grooves covered with a translucent material impervious to actinic light, one or more of said scales being transparent, or translucent, so that the same can be viewed by a light in the printer and below said grooves.

And another object is to provide a masking means of the type set forth in which each of two adjustable masks, in addition to carrying the margin scale, also carries a scale indicating one dimension of the exposed area of the paper so that when a third mask is adjusted over said last-mentioned scale, the dimension of the ex-

posed area indicated by the scale is exclusive of the margin previously adjusted for.

Still another object is to provide a contact printer in which the printing window is more uniformly illuminated over its entire area than heretofore possible with printers of this type.

And another object is to provide a masking means of the type set forth which in addition to being easy and accurate to adjust, along with the fact that it can be readily adjusted in a darkroom, is inexpensive to manufacture and pleasing in appearance.

The novel features that we consider characteristic of our invention are set forth with particularity in the appended claims. The invention itself, however, both as to its organization and its methods of operation, together with additional objects and advantages thereof, will best be understood from the following description of specific embodiments when read in connection with the accompanying drawing in which,

Fig. 1 is a top plan view of a photographic contact printer, with the platen in a raised position, and incorporating a paper masking means constructed in accordance with a preferred embodiment of the present invention.

Fig. 2 is a sectional view taken substantially on lines 2—2 of Fig. 1, but showing the platen in a lowered, or paper holding position.

Fig. 3 is a sectional view taken substantially on lines 3—3 of Fig. 1.

Fig. 4 is a sectional view taken substantially on lines 4—4 of Fig. 1.

Fig. 5 is a sectional view taken substantially on lines 5—5 of Fig. 1, and showing the manner of mounting the paper guide on the top of the printer so as to be adjustable to and from the same.

Like reference characters refer to corresponding parts throughout the drawing.

Referring now to the drawing, our new and novel paper masking means is shown incorporated on the photographic contact printer comprising an enclosed housing 10 within which is situated the usual printing lamp 11 and a small safelight lamp 12. The top wall 13 of the housing 10, which may be referred to as a supporting surface for a sensitive paper, includes a clear window 14 on which a negative to be printed is adapted to be placed in superposed relation with a sensitive paper, the light from the printing lamp 11 passing through the window to make the exposure.

That portion of the top wall of the housing 10 immediately surrounding the window is turned

downwardly to provide a printing apron 15, and the face of said apron directed toward the window may be painted white, as is the entire interior of the housing, to reflect the rays of light from the lamp to the edges of the window. We have found that this apron 15 makes for a more uniform illumination of the window 14 than is possible without it, with the result that the contact print is more uniformly exposed over its entire area than heretofore possible. This desirable uniform exposure is due to the fact that the rays of light from the lamp 11 which would ordinarily pass into the upper corners of the housing at an angle past the window are reflected by said apron back through the edges of the window. Redirecting these slanting rays of light, which would ordinarily be lost without the use of the apron 15, back through the edges of the window increases the illumination at the edges of the window and tends to overcome an uneven illumination of the window, the center of the window ordinarily receiving more light than the edges due to the fact that the lamp is located directly below the center thereof.

The superposed negative and sensitive printing paper positioned above the window 14 is adapted to be held in a flat position by a platen 16 connected to the top wall 13 by a hinge 17, one portion 18 of which is fixed to an inclined wall 19 of a recess 20 in the top wall, see Fig. 2. The platen 16 may, as shown, comprise two sections 21 and 22 hinged together by a hinge 23 so that the forward section 22 may be raised independently of the rearward section 23, as is well known. As is the usual practice, the lower face of the two sections of the platen may be felt or other suitable resilient material. A handle 25 is connected to the forward platen section 22 for raising and lowering the platen. This handle, as shown in Fig. 2, extends forwardly over the front wall 26 of the housing 10 and terminates in thumb piece 27. The intermediate portion of the handle 25 is bridged as shown at 28 to accommodate one member of the paper masking means hereinafter set forth, see Fig. 2.

Attached to the under side of the handle 25 is a latch 29 which, due to the resiliency inherent in the same, normally snaps into locking engagement with a latch element 30 on the front wall of the housing when the platen is lowered, and for the purpose of locking the platen in its lowered position, see Fig. 2. Fixed to the latch 29 is a finger-piece 31 located directly below and spaced from the thumb-piece 27. By gripping the thumb-piece 27 and the finger-piece 31 between the thumb and forefinger the latch 29 may be sprung away from the latch element to permit the platen to be raised. As is common practice in contact printers, it is desirable to have the printing light automatically turned on the instant the platen is closed. To this end an arm 32 integral with the latch 29 is adapted to engage and close the normally open switch 33 adapted to be connected in circuit with the printing lamp, as is well known, when the platen is in its lowered position, said switch being located in a recess 34 formed in the upper corner of the front wall 26. The ruby safelight 12 will, as customary, be on at all times when the printer is in use and may be controlled by a separate switch, not shown, which may be on the printer proper, or which may be in the electrical cord connecting the printer to a source of electrical energy.

In making prints from a negative it is desir-

able to be able to obtain different margins on the prints, and it is also imperative that the exposed area of the window be variable to accommodate different sizes of negatives as well as different sizes of printing paper. To this end the new and novel masking means hereinafter set forth has been invented by us.

A paper guide 35 is fixed to the top wall 33 by an adjusting screw 36 passing therethrough and being threaded into the top wall of the housing. Between the paper guide and the top wall two bowed screens 37 are situated in recesses in the top wall, see Fig. 5, said springs normally tending to force the paper guide upwardly from the surface of the top wall. The upward movement of the paper guide under the action of the bowed screens is limited by two posts 24 passing freely through the guide and being screwed into the top wall of the housing, the paper guide being 20 slidable relative to the shanks of said posts and adapted to come to rest against the under side of the head thereof. The paper guide 35 includes two perpendicular intersecting paper guiding edges 38 and 39 into abutment with which 25 the corner of a sensitive paper is adapted to be placed for squaring the paper with respect to the window 14, see Fig. 5. The paper guide 35 is located on the top wall 13 so that the respective paper guiding edges thereof will be parallel to two adjoining edges of the window 14 and will be spaced a definite distance therefrom. In the present instance the paper guide is located so that the guiding edges thereof are one-quarter of an inch from the edges of the window whereby 30 a paper located thereby will have a one-quarter of an inch margin on two adjoining edges. However, it will be readily appreciated that the paper guides could be located in any position relative to the window, e. g., with the guiding edges 35 thereof flush with the edges of the window so that no margin would be placed on the paper when positioned by the guide. The paper guide is preferably mounted to move to and from the top of the housing as shown so as to provide a 35 clamp for the negative and to permit free adjustment of one of the mask strips as will be set out below.

The top wall 13 of the housing 10 is provided with two elongated slots 40, 40' in perpendicular relation, one of said slots extending parallel to one guiding edge 38 of the paper guide 35 and the other slot extending parallel to the other guiding edge 39 of the paper guide. Each slot 40 is surrounded by the downwardly extending flange 41 into grooves in which a sheet of translucent material 42, impervious to actinic light, extends. These sheets of translucent material may be the same as ordinarily used for safelights, e. g., colored glass, colored plastics, etc. We have found that a red plastic material serves the purpose very well.

Slidably mounted in or above each of these slots 40 is a pair of sliders 43 and 44 and to each of which is connected a mask strip 45, which may consist of a flat piece of thin metal, and which extends across the window 14 in parallel relation to the edges thereof. The two sliders in each slot are constructed and operated in the same manner so that only one pair will be described in detail; the corresponding ones of the other pair being referred to by the same reference characters primed (').

One slider 43 of each pair is attached by a screw 46 extending therethrough, to a margin scale 47 slidably held in the slot 40 by a pair of

flanges 48 thereon engaging flanges 49 overhanging the top of the slot, see Figs. 3 and 4. This margin scale extends from one side of the slider and includes a scale 50 on its upper face marked in one-quarter inches, or other suitable margin designations. Each margin scale is adapted to cooperate with an index 51 on the top wall of the housing adjacent the slot and definitely located relative to one guiding edge of the paper guide 35. Each mask strip is firmly held at one end between the slider and upper surface of the margin scale 47 by the screw 46, and to insure said strip extending perpendicularly from the slot, and to prevent the same from rotating relative to the slider, the strip may be provided with two spaced holes 52 adapted to slip over a pair of pins 53 on the margin scale 47. A washer 65 may be placed between the under side of each slider and the mask strip connected thereto to give plenty of clearance between the under side of the slider and the top wall of the housing so that the slider will be free to move along in the slot 40. The index 51 is so positioned on the top wall that when the slider 43 is moved to position the one-quarter inch mark on the margin scale 47 opposite the index the inner edge of the mask 45 connected to said slider is flush with one edge of the window. With such a setting the edge of the paper located above and adjacent this mask by the paper guide 35 is provided with a one-quarter inch margin due to the fact that the paper guide is located with its guiding edges one-quarter inch from the edges of the window. If the slider is moved until the one-half inch mark on the margin scale 47 connected thereto is opposite its respective index, as shown in the drawing for slider 43' and its associated parts, then the inner edge of the mask strip connected thereto will be one-quarter of an inch inside of the edge of the window covered thereby, and which one-quarter of an inch added to the one-quarter of an inch provided by the location of the paper guide will give a one-half inch margin on the paper as indicated by the scale reading. It will be readily appreciated that if desired the paper guide could be located with its paper guiding edges flush with the edges of the window so that the mask strip would give the entire margin, the scale and index setting necessarily having to be rearranged to fit such a change; but since a one-quarter inch margin is the least that is generally required on a print, the disclosed arrangement is entirely satisfactory. In order to restrict the movement of the sliders 43, 43' in the slots 40, 40' against too free movement, a bowed spring 54 may be located in the recess 57 in the edge of the margin scale 47 connected thereto to engage the longitudinal wall of the slot as clearly shown in Fig. 4.

An elongated scale 55, 55' is slidably mounted in each slot 40, 40' and is connected to the sliders 43, 43' by a pin 56, passing through one end thereof and one end of the margin scale 47, whereby said scales 55, 55' are adapted to move with said sliders 43, 43'. This scale extends from the slider in a direction opposite that of the margin scale 47 and is marked in inches, its purpose being to designate the dimensions of the area exposed by each pair of parallel masking strips. This scale is made of a translucent material, such as glass or plastic, and has scale markings of an opaque nature thereon whereby such markings are readily visible in the colored light passing through the strip 42 and the scale itself.

A pointer 58 is slidably mounted in the slot 40 above the scale 55 in the same manner as set forth for margin scale 47, and a mask strip 45 and slider 44 is connected thereto as set forth above in describing the connection of the mask strip 45 and slider 43 to the margin scale 47. When the slider 44 is moved relative to slider 43 the end 59 of the pointer moves over the scale 55 and its position on said scale indicates the dimension of the area exposed defined by the inside edge of the mask strip to which it is connected and the mask strip parallel thereto and sliding in the same slot 40. Referring to Fig. 1 it will be noticed that the end 59 of the pointer 58 on the slider 44 is located at 5½ inches on the scale 55, while the end 59' on the pointer 58' is located at 3¾ inches on the scale 55', thus showing that the mask strips are set to give an exposed area 5½ inches by 3¾ inches. The scales 55 and 55' normally appear as red due to the light transmitted therethrough, and when the pointers, which are preferably opaque, are moved thereover, the positions of the ends thereof are readily discernible in a darkroom.

With the mask strips set as shown in Fig. 1 the scales clearly indicate that the print will have a ½-inch margin on one side, a ¼-inch margin on the adjoining side, a picture area 3¾ of an inch long on the side having the ½-inch border and 5½ inches long on the side having the ¼-inch margin. If the printing paper has overall dimensions of 6 inches by 4¾ inches the opposite margins will be equal. Ordinarily the margins are equal on all sides of a print so that the two margin scales will be set alike. However, to clearly illustrate the adjustable features of our mask we have shown the two margin scales set differently. It will be readily appreciated that if the overall size of the printing paper being used is known then by setting the sliders 43, 43' to a given margin on two adjoining edges of the paper then the sliders 44, 44' can be adjusted to give an exposed area having equal margins on the other two edges. Or, if a given exposure area is required then the sliders 43, 43' can be adjusted to give a margin on two adjoining edges of the paper one-half of the difference between the size of the paper and said picture area so that any two opposite margins will be equal to each other.

It will be noticed that one of the mask strips 45' extends beneath the paper guide 35 by reason of the particular arrangement of parts. This makes it necessary that the paper guide adjusting screw 36 be loosened sufficiently to permit the mask strip to be adjusted beneath the paper guide after which the screw can be tightened down to clamp the mask strip and the negative at the same time.

So that small picture negatives, e. g., 35-mm., etc., can be printed in strip form with this printer the paper guide 35 is provided with one of the posts 24 spaced from the adjusting screw 36 a distance substantially equal to the width of such film, and each of the two screws are provided with a circumferential groove indicated at 61 for readily receiving and guiding the edges of the film strip of the character mentioned, and indicated in dotted lines on Fig. 1 and designated by F. The sliders 43 and 44 are provided with grooves 62 into which the edges of the miniature film F may extend when the two sliders are moved into guiding relation with one another and the adjusting screw 36 and one of the posts 24 see, see Fig. 1. When the sliders 43 and 44 are

moved to this position the two mask strips 45 carried thereby are spaced apart correctly for the width of such negatives, and the slider 44' is moved toward the slider 43' to move the mask strips 45, 45' connected thereto apart a distance equal to the length of said miniature negatives. When contact prints are being made from these smaller negatives only the front section 22 of the platen need be raised to permit insertion and removal of the sensitive printing paper. The corner of the paper guide 35 adapted to be crossed by the strip of miniature negative is bevelled, as shown at 63 in Figs. 1 and 5 to permit the platen to flatten the negative on the window without tending to score the negative over a sharp corner and abnormally deform the felt, or rubber, on the platen face.

The use and operation of the novel masking means set forth will now be described. The platen 16 will first be raised and the ruby safelight 12 will be turned on. Then supposing a 3 x 5 inch picture is to be printed on a printing paper 4 inches by 6 inches. This will mean a $\frac{1}{2}$ -inch margin will be needed all around the paper. The adjusting screw 36 is loosened to permit the paper guide 35 to raise and free the mask strip 45' clamped thereby. The slider 43' is then moved until $\frac{1}{2}$ inch on the scale 50 of the margin scale 47 connected thereto is opposite the index 51' and then the negative is slipped under the paper guide and the adjusting screw 36 tightened down again. Next the slide 43 is moved until the $\frac{1}{2}$ -inch mark of the scale 50 on the margin scale 47 is opposite the index 51. The slider 44' is then moved until the end 59' of the pointer 58 connected thereto is in alignment with the 3-inch mark on the scale 53', and the slider 44 is moved until the end 59 of the pointer 58 connected thereto is in alignment with the 4-inch mark on the scale 55. These adjustments correctly set the mask strips 45, 45' to give the print size and margins specified, and all that remains to be done is to place the paper on top the mask strips with one corner thereof in abutment with the guiding edges of the paper guide 35, being sure that the paper is turned so that the long side thereof corresponds to the longer dimension defined by the mask strips; and then closing the platen 11 onto the paper. The margin scales 47, 47', and the indices 51, and 51' could be made transparent if desired to facilitate seeing them in the dark, but we have found that there is enough light emanating from the slots 40, 40' around the same so that a white scale 50 and a white index are clearly discernible in total darkness.

While we have shown and described our novel masking means in combination with a contact printer it is pointed out that the same could be readily used on the easel of a projection printer. The masking means would function in the same manner, the only difference being that the printing paper would then be located beneath the mask strips instead of on top of the same, and the one mask strip 45' would have to move above the paper guide 35 rather than under it.

From the above description it will be readily understood that a contact printer constructed in accordance with our invention possesses several advantages over those of the prior art. It includes a versatile paper masking means by means of which the margins and picture areas of prints can be rapidly and accurately adjusted to any desired dimension. The masking means is suitable for both contact and projection printing

apparatus. The masking means is such that it can be readily adjusted in the dark without danger of fogging any sensitive paper lying exposed near-by. Further, the apron extending into the printer around the window provides a more even illumination over the entire window than heretofore possible with similar apparatus with the result that a contact print made thereon has a uniform exposure over the entire picture area rather than a strong exposure at the center and falling off at the edges as was found to be true of known contact printers of the prior art.

While we have shown and described certain specific embodiments of our invention, we are aware that many modifications thereof are possible. Our invention, therefore, is not to be restricted except insofar as is necessitated by the scope of the appended claims.

Having thus described our invention what we claim is new and desire to secure by Letters Patent of the United States is:

1. In a photoprinting machine the combination of a paper support, a paper guide occupying a definite position on said support and including two perpendicular intersecting edges against which a corner of a light sensitive paper may be abutted to square the same on the support, a masking means for protecting the margins of said paper from a beam of light directed toward said paper, and including a marginal mask extending parallel to one edge of the paper guide, a second marginal mask extending parallel to the other guiding edge of said paper guide, each of said masks slidably mounted on said paper support to move transversely of its length, two indices on said support, each one being located in a definite relation to a different guiding edge of said paper guide, and a margin scale connected to each of said masks to move therewith and adapted to cooperate with one of said indices whereby said mask strips are adapted to be readily adjusted to cover a desired margin on two adjacent edges of a paper positioned by said paper guide.

2. In a photoprinting machine the combination of a paper support, a paper guide occupying a definite position on said support and including two perpendicular intersecting edges against which a corner of a light sensitive paper may be abutted to square the same on the support, an adjustable masking means for protecting the margins of said paper from a beam of light directed toward said paper and for determining the exposed area of said paper, and including four marginal masks in rectangular arrangement, the four masks being individually adjustable on the support with respect to one another and with respect to the paper guide, two of said intersecting masks extending parallel to the guiding edges of said paper guide, two indices on said support, each one being located in a definite relation to a different guiding edge of said paper guide, a margin scale connected to each of two intersecting masks and adapted to cooperate with one of said indices to permit the masks carrying the same to be readily adjusted to cover a desired margin on two adjacent edges of a paper positioned by said guide, a second scale connected to each of the masks carrying said margin scales and movable therewith, a pointer carried by each of said other two masks and adapted to cooperate with one of said last mentioned scales when said last mentioned masks are individually adjusted relative to said first mentioned two masks, and for indicating the dimensions of the area bounded

by said masks and exposed to light directed toward the paper.

3. In a photoprinting machine the combination with a support having a window through which light may pass, a paper guide occupying a definite position on said support with respect to said window and including two perpendicular paper guiding edges, of a masking means including two marginal mask strips in perpendicular relation and independently adjustable relative to each edge of said paper guide, two indices on said support, each located in definite relation to one guiding edge of said paper guide, a margin scale connected to each of said mask strips to move therewith, each of said margin scales adapted to cooperate with one of said indices when the masks are individually adjusted to facilitate the setting of said masks to cover a desired margin on two adjacent edges of a paper positioned by said paper guide.

4. In a photoprinting machine the combination with a support having a window through which light may pass, a paper guide occupying a definite position on said support with respect to said window and including two perpendicular paper guiding edges, of a masking means including four marginal mask strips in rectangular arrangement and individually adjustable with respect to one another and the paper guide, two indices on said support, each located in definite relation to one guiding edge of said paper guide, a margin scale connected to each of two adjoining masks to move therewith and adapted to cooperate with one of said indices when the masks carrying the same are individually adjusted to facilitate the setting of said masks to cover a desired margin on two adjacent edges of a paper positioned by said guide, a second scale connected to each of the masks carrying said margin scale and adapted to move therewith, a pointer carried by each of said other two masks and adapted when the masks are individually adjusted to move over the second mentioned scale carried by the mask parallel thereto to indicate the dimensions of the area bounded by said four masks.

5. In a photoprinting machine the combination with a support having a window through which light may pass, a paper guide occupying a definite position on said support with respect to said window and including two perpendicular paper guiding edges, of a masking means for a paper positioned by said paper guide and including a pair of grooves in said support adjacent said window, one groove extending parallel to one guiding edge of the paper guide and the other extending parallel to the other guiding edge of the paper guide, a pair of sliders individually

slidable in each of said grooves, a mask strip connected to each of said sliders and extending perpendicularly of the groove across said window, two indices on said support adjacent each of said grooves and each definitely located relative to one guiding edge of said paper guide, a margin scale connected to one slider in each groove to move therewith in said groove and adapted to cooperate with one of said indices to facilitate the setting of the masks carried by said sliders to cover a desired margin on two adjacent edges of a paper positioned by said guide, a scale connected to the same sliders to move in said groove therewith when they are adjusted, and a pointer on each of said other two sliders in overlapping relation with said second mentioned scales to indicate the dimensions of the area bounded by the four masks.

6. In a photoprinting machine the combination with a support having a window through which light may pass, a paper guide occupying a definite position on said support with respect to said window and including two perpendicular paper guiding edges, of a masking means for a paper positioned by said paper guide and including a pair of slots in said support adjacent said window, one slot extending parallel to one guiding edge of the paper guide and the other extending parallel to the other guiding edge of the paper guide, a strip of translucent material impervious to actinic light attached to the underside of said support in covering relation with each of said slots, a pair of sliders individually slidable in each slot above said translucent material, a mask strip connected to each of said sliders and extending perpendicularly of the slots across said window, two indices on said support adjacent each of said slots and each definitely located relative to one of the two guiding edges of said paper guide, a margin scale in each slot and connected to one slider in said groove to move therewith, each of said margin scales adapted to cooperate with one of said indices to facilitate the setting of the masks carried by said sliders to cover a desired margin on two adjoining edges of a paper positioned by said guide, a transparent scale in each of said slots and connected to the slider carrying said margin scale to move therewith as the same is adjusted, and a pointer connected to the other slider in each groove to move therewith as the same is moved to adjust the mask connected thereto, said pointer overlapping said transparent scale to indicate the dimensions of the area bounded by the four masks.

FORDYCE E. TUTTLE.
JOSEPH STOIBER.
